United States Patent Office.

JOHN D. FLANSBURG, OF PHILADELPHIA, ASSIGNOR TO SEYMOUR RAYMOND AND JOSEPH CAMPBELL, OF MIDDLETOWN, PENNSYLVANIA.

Design No. 4,400, dated October 11, 1870.

DESIGN FOR A STOVE.

The Schedule referred to in these Letters Patent and making part of the same.

To all whom it may concern:

Be it known that I, JOHN D. FLANSBURG, of Philadelphia, in the county of Philadelphia, and State of Pennsylvania, have invented a new and improved Design for a Stove; and I do hereby declare the following to be a full, clear, and exact description of the same, reference being had to the accompanying drawings making a part of this specification, in which the figure is a perspective view.

The design relates to a cylinder stove surmounted by a cubical casing, which is mostly taken up as an oven, the door through which the cylinder is supplied with fuel being in the casing below the oven.

My design also extends to a shell placed outside of the cylinder, for the purpose of hiding it, when the exterior of said shell is ornamented with circumferential rows of uniform shield-shaped depressions.

In the drawings—

a is the shell that incloses the cylinder.

b are the shield-shaped concavities in the exterior of the shell *a*, the said concavities being arranged in circumferential rows, one row above another.

There are orifices in the shell, between the points

of the concave plates *b* of the lower row and between the heads of the concave plates of one row and the points of the concave plates of the next row above, the function of said orifices being to afford escape for the air heated between the cylinder and the shell; but the perforations of the shell form no part of my design.

The surmounting casing is lettered *c*.

d is the offset, projecting downward from the central portion of the front side of the casing.

e is the door, placed partly in the offset *d* and partly in the casing above it.

Having thus described my invention,

What I claim as new, and desire to secure by Letters Patent, is—

1. The design for the combined casing *c*, offset *d*, and door *e*, as herein shown.

2. The design for the shell *a*, as herein shown.

JOHN D. FLANSBURG.
